UNITED STATES PATENT OFFICE

121,143

DESIGN FOR A TEXTILE FABRIC

Howard Veit, New York, N. Y.

Application February 17, 1940, Serial No. 90,332

Term of patent 3½ years

To all whom it may concern:

Be it known that I, Howard Veit, a citizen of the United States, residing at #1010 Fifth Avenue, city of New York, State of New York, county of New York, have invented a new, original, and ornamental Design for a Textile Fabric, of which the following is a specification, reference being had to the accompanying drawing, forming part thereof.

The figure is a plan view of a textile fabric showing my design.

I claim:

The ornamental design for a textile fabric, as shown.

HOWARD VEIT.
